UNITED STATES PATENT OFFICE.

WELLINGTON S. ROBINSON, OF CHICAGO, ILLINOIS, ASSIGNOR TO THE YALE & TOWNE MANUFACTURING COMPANY, OF STAMFORD, CONNECTICUT.

LOCK.

No. 874,793.

Specification of Letters Patent.

Patented Dec. 24, 1907.

Application filed September 3, 1907. Serial No. 391,157.

To all whom it may concern:

Be it known that I, WELLINGTON S. ROBINSON, of Chicago, in the county of Cook and State of Illinois, have invented certain new and useful Improvements in Locks; and I do hereby declare the following to be a full, clear, and exact description of the invention, such as will enable others skilled in the art to which it appertains to make and use the same.

My invention relates to an improvement in locks adapted particularly for use on exit doors of theaters, halls, etc., the object being to provide means, whereby in the case of a panic, or desire on the part of those on the inside to get out, the lock bolt may be retracted and the door swung open, by pressure applied to a yielding member on the inner face of the door.

With this end in view my invention consists in a bolt, knob mechanism for actuating same, and a swinging plate mounted on the inner face of the door and adapted when forced toward the door, to retract the locking bolt and release the door, thus permitting the latter to swing open.

My invention further consists in the parts and combinations of parts as will be more fully explained and pointed out in the claims.

In the accompanying drawings, Figure 1 is a view in vertical section through a section of a door with my improved lock thereon. Fig. 2 is a view in elevation of a portion of the door showing the swinging plate and Fig. 3 is a view in elevation of the lock the cover plate being removed.

While I have shown a lock having a single bolt, I may employ two or three bolts, in which event the several bolts would be connected by levers or other devices so as to be actuated in unison.

1 represents lock case adapted to be secured within a mortise in the edge of a door.

2 is the outer escutcheon plate carrying a pin tumbler or cylinder lock 3 and a knob 4, the spindle 5 of which carries the roll back 6.

Mounted on stud 7 carried by the roll back, is the link 8, the lower end of which carries a stud 9 resting in the elongated slot 10 in bolt carrying member 11. The bolt 12, shown in Fig. 1, is secured in a socket 13 in the lower end of member 11 and projects downwardly to the lower end of the door and engages a keeper secured to the door sill.

The upper end of member 11 is provided

with an elongated slot 14 through which the knob spindle 5 passes, which slot together with the slot in the lower end of the lock case 1, guides the member 11 and bolt 12 in their vertical movements.

With the construction of parts thus far described, it will be seen that the weight of the bolt tends to keep the latter in its locking position, the elongated slots in the member 11 permitting of movement of the bolt independently of the knob mechanism. By rotating the knob, the roll back 6 will be turned, thus lifting link 8; this upward movement of link 8 causes stud 9 to engage the upper wall of slot 10 in member 11, thus elevating the latter and the bolt 12 carried thereby.

In order to lock the knob, which is on the outside of the exit door, I have provided the deadlocking slide 15, actuated by the pin tumbler or cylinder lock 3. This slide 15 is suitably mounted in the lock case 1, and is provided with two lips 16 and 16^a, the former of which is engaged by the arm 17 on the hub or barrel of the lock 3, when the latter is turned in a direction to move the slide toward the roll back, and the lip 16^a is engaged by the arm 17 when the latter is turned in a direction to move the slide away from the roll back. Located intermediate the lips 16 and 16^a is the tongue 17, on the tumbler 18, which latter is carried by the slide 15 and held in the position shown in Fig. 3 by the spring 19. When in the position shown, a shoulder on the tumbler is in engagement with a lug 20, which holds the slide against accidental movement when not in engagement with the roll back. The slide is provided with the toe 20^a which latter is adapted to enter the recess 21 in the roll back and lock the latter against movement. One recess 21 is located in a position to deadlock the bolt in its locked position and the other is ninety degrees removed, so that when the roll back is given a quarter turn this second recess is brought into position to register with the toe and thus deadlock the bolt in its retracted position.

With this lock, the cylinder or pin tumbler lock simply operates to deadlock the knob mechanism, the latter being the sole means for retracting the bolt from the outside.

Secured to the inner face of the lock stile of the door is a metal frame 29 provided near

its lower end with the pivoted bell crank lever 23, one end 24 of which rests within a slot 25 in the bolt and engages the upper wall of said slot, while the outer member 26 of said lever 23, is engaged by shoulder 27 on the inner face of plate 28 hinged at its upper end to the frame 29. As the lever 23 is in the form of a bell crank lever, and is fulcrumed intermediate its ends, it will be seen that when the plate 28 is forced or swung inwardly, the latch will turn on its pivot, and the member 24 being in engagement with the bolt, (when the latter is in its locking position) will elevate the bolt and thus release the door. This plate 28 is of considerably greater length than the lock, and is located on the inner face of the door in the place where one would naturally push in an effort to force the door, hence in the event of a panic or stampede in a theater or other hall, a pressure against the plate 28 automatically withdraws all the bolts and opens the door.

The lock may have a bolt to engage a keeper in an adjacent swinging door, consequently by retracting the bolts as above explained both doors will be free to open.

With this lock the doors may be safely locked against entrance except by the use of the proper key, and always be in a condition to be automatically unlocked by a pressure applied to the swinging plate 28.

It is evident that many slight changes might be resorted to in the relative arrangement of parts shown and described without departing from the spirit and scope of my invention hence I would have it understood that I do not wish to confine myself to the exact construction of parts shown and described, but,

Having fully described my invention what I claim as new and desire to secure by Letters-Patent, is:—

1. The combination with a bolt, outside mechanism for retracting same and means for dogging the latter, of a yielding means secured to the inner face of the door and de-

vices connecting the bolt and said yielding means, whereby when pressure is applied to the latter the bolt will be retracted.

2. The combination with a bolt, mechanism for retracting same from the outside of the door the said bolt having free movement independent of said outside mechanism, and means for dead-locking the outside mechanism, of a yielding device exposed at the inner side of the door and means connecting said bolt and yielding device whereby when pressure is applied to the latter, the bolt will be retracted.

3. The combination with an outside knob, knob mechanism and a bolt, the latter having a free movement independent of the knob mechanism, of a yielding device exposed at the inner side of the door and means connecting said bolt and yielding device, whereby when pressure is applied to the latter the bolt will be retracted.

4. The combination with a door, outside means for retracting the bolt, means for deadlocking said outside means and a bolt actuated by the latter, of a plate hinged to the inner face of the door and means connecting said plate and bolt, whereby when pressure is applied to the former, the bolt will be retracted.

5. The combination with a door, outside means for retracting a bolt, means for deadlocking said outside means and a bolt actuated by the latter, of a plate hinged at its upper end to the inner face of the door, and a pivoted lever engaging the inner face of the hinged plate and the bolt, whereby when the plate is swung toward the door, the bolt will be retracted.

In testimony whereof, I have signed this specification in the presence of two subscribing witnesses.

WELLINGTON S. ROBINSON.
